UNITED STATES PATENT OFFICE.

JOSEPH C. GITHENS, OF NEW YORK, N. Y., ASSIGNOR TO RAND DRILL COMPANY, OF SAME PLACE.

STEAM ROCK-DRILL.

SPECIFICATION forming part of Letters Patent No. 233,501, dated October 19, 1880.

Application filed July 8, 1880. (No model.)

To all whom it may concern:

Be it known that I, JOSEPH C. GITHENS, of the city and State of New York, have invented certain Improvements in Steam Rock-Drills, 5 of which the following is a specification.

My improvements relate to the class of steam rock-drills in which the rotating feed motion is imparted to the piston which carries the drill by means of a spiral guide-rod, which 10 engages a nut fixed centrally in the end of the piston. As the piston reciprocates this nut traverses the spiral guide-rod, and either imparts a rotary motion thereto or derives a rotary motion therefrom, accordingly as the spiral guide-rod is itself left free to rotate or is prevented 15 from rotation by friction exerted upon its head by means of steam-pressure. This friction upon the head of the guide-rod is exerted by means of live steam introduced into the bottom or extreme inner end of the cylinder, 20 where it acts either upon a supplemental piston or upon a diaphragm, which is thus made to bear upon the head of the spiral guide-rod and hold it firmly upon its seat during the inward movement of the piston which carries the 25 drill. In operation, however, there is a rebound of the drill at each blow, which enlarges the live-steam space beneath the piston and correspondingly contracts the exhaust-steam 30 space between the inner end of the piston and the piston or diaphragm which bears upon the head of the spiral guide-rod. It thus sometimes happens that the steam-pressure in the exhaust-space exceeds the steam-pressure upon 35 the supplemental piston or diaphragm, and by lifting the latter frees the head of the guide-rod from friction. The guide-rod is thus permitted to rotate instead of remaining stationary, and causing the rotation of the piston carrying the drill.

It is the object of my improvements to overcome this difficulty; and my present invention consists, mainly, in combining with the steam-chamber, between the bottom of the cylinder 45 and the supplemental piston or diaphragm, which, for convenience, I call the "supplemental steam-chamber," a check-valve which yields inwardly to admit steam into the supplemental steam-chamber, but closes in case 50 the pressure in the live-steam space beneath

the drill-piston is diminished by the rebounding of the drill.

In order to open the check-valve and permit the escape of steam from the supplemental steam-chamber I provide the check-valve 55 with a lateral arm, which projects so far into or across the supplemental steam-chamber as to be struck and be lifted by the supplemental piston or diaphragm at the conclusion of the upward stroke of the drill-piston, when 60 the supplemental piston or diaphragm is acted upon by live steam introduced into the cylinder between the drill-piston and the supplemental piston or diaphragm. Steam is thus introduced just before the conclusion of the 65 upward stroke of the drill-piston, and is given access to the inner face of the supplemental piston or diaphragm through longitudinal perforations in the head of the spiral guide-rod and the seat upon which the head of the guide- 70 rod bears.

In the accompanying drawings, representing a steam rock-drill embodying my improvements, Figure 1 is a central longitudinal section through the drill-cylinder, showing the 75 supplement piston, the head of the spiral guide-rod and its seat, and a portion of the drill-piston in section, and showing the spiral portion of the guide-rod and a portion of the drill-piston in elevation, this section being taken through the line *w w* on Fig. 2. Fig. 2 is a transverse section through the line *x x* on Fig. 1. Fig. 3 is a central longitudinal section of a portion of the drill-cylinder through the line *y y* on Fig. 2. Fig. 4 is a transverse section of the drill- 85 cylinder through the line *z z* on Fig. 3.

The drawings represent my improvements applied to a steam rock-drill like that described in Letters Patent of the United States No. 158,060, granted to me, for improvements in 90 steam rock-drills, December 22, 1874.

The drill-cylinder *A* is provided with suitable valve-gear, by means of which steam is alternately admitted through the steam-passages *B* and *C*, into the steam-spaces *B'* and *C'*, for 95 the purpose of acting upon the opposite ends, respectively, of the drill-piston *D*. The inner portion of the drill-piston is longitudinally recessed to admit the spiral guide-rod *Q*, which is engaged by the nut *R*, centrally affixed to 100

the inner end of the drill-piston. The spiral guide-rod Q is provided with an annular flange, q, which has its bearing upon the annular shoulder q', affixed to the interior of the cylinder A. 5 This shoulder also forms the seat for the head S of the spiral guide-rod. The head S is a perforated disk secured upon the upper end of the spiral guide-rod by the jam-nut S'.

The shoulder q' is provided with longitudinal perforations q² and the annular groove q³, for the admission, at the proper time, of live steam through the perforations s in the head of the spiral guide into the space between the head S and the supplemental piston T. The 15 supplemental piston is provided with a transverse key-rib, T', which is engaged in a corresponding groove formed across the inner face of the cap U of the cylinder. The object of this construction is to prevent the supplemental 20 piston from rotating, and the key-rib T' is therefore made sufficiently high and its groove sufficiently deep to provide for the reciprocation of the supplemental piston without the disengagement of the key-rib T' from its groove.

25 The supplemental piston is acted upon by live steam introduced into the supplemental steam-chamber T² through the steam-passage b, which receives its supply of steam from the principal steam-passage B. The supplemental 30 steam-chamber T² would be in constant communication with the steam-space B' but for the check-valve E. The stem e of the check-valve is provided with an expanding spiral spring, e', which is made to yield by the pressure of 35 live steam in the passage b upon the valve E, thus permitting the opening of the valve E and the introduction of live steam into the supplemental steam-chamber T².

It will be seen that by this mode of organization 40 the check-valve will drop upon its seat if, after the introduction of live steam into the supplemental steam-chamber T², there is any diminution of pressure in the steam-space B', and consequently in the steam-passages B and 45 b, such as may arise from the rebounding of the drill. By the closing of the check-valve the steam-pressure upon the supplemental piston T, and consequently upon the head S of the spiral guide-rod, will be persistently 50 maintained until the instant when the drill-piston concludes its upward stroke and live steam is introduced into the steam-space C', to effect the downward stroke of the drill-piston. At this instant the pressure of the steam 55 in the steam-space C', acting through the passages q² and o upon the under side of the supplemental piston T, will raise the supplemental piston, carrying up the arm E', projecting laterally inward from the check-valve E, thus 60 opening the check-valve and allowing the exhaust-steam to escape from the supplemental chamber T².

During the downward movement of the 65 drill-piston the spiral guide-rod will be free to rotate owing to the absence of steam from the supplemental steam-chamber T² and the con-

sequent absence of pressure upon the head S of the guide-rod. Just before the conclusion of the downward stroke of the drill-piston live steam is admitted into the steam-space B' through the steam-passage B, and hence through the steam-passage b into the supplemental chamber T², thus again causing the downward movement of the supplemental piston T and the application of friction to the head S of the guide-rod.

The supplemental piston T is, it will be seen, a clamp worked by steam, and its automatic operation as a steam-clamp for the head of the spiral guide-rod is rendered much more 80 certain and effectual by the presence of the check-valve which I have described, and also of the device in the nature of a key, which prevents the possibility of its own rotation.

It will of course be understood that the 85 check-valve may, if desired, be opened at the conclusion of each upward stroke of the drill by a positive motion derived directly from the drill-piston or from the drill piston-rod and transmitted by means of a sliding rod, the 90 thrust of which would be received either upon the laterally-projecting arm E' or upon a laterally-projecting tappet affixed to the check-valve stem e, in which latter case the check-valve stem e might be lengthened and made 95 to extend through the end or cap U of the cylinder, so that the lateral tappet could be affixed to it externally. On account of its greater simplicity, however, I prefer the form of construction shown in the drawings, in 100 which the thrust which opens the check-valve is delivered upon the arm E', which projects into the supplemental steam-chamber.

I claim as my invention in a steam rock-drill substantially such as described—

105

1. In a steam rock-drill, the supplemental steam-chamber T² and the steam-passage b, provided with the spring check-valve E, in combination with the steam-space B' and the drill-piston D, substantially as set forth.

110

2. In a steam rock-drill, the spiral guide-rod Q, in combination with the supplemental piston T, the key-rib T', and its seat, for the purpose of preventing the rotation of the supplemental piston, substantially as described.

115

3. In a steam rock-drill, the check-valve E, provided with the lateral projection E', for receiving the thrust by which the spring check-valve is opened at the conclusion of each upward stroke of the drill-piston D, as set forth.

120

4. In a steam rock-drill, the combination of the cylinder A, the drill-piston D, and the steam-passages B and C with the supplemental piston T, the friction-plate S, and spiral guide-rod Q, the steam-passage b, and the spring check-valve E, substantially as described.
